Application November 29, 1939, Serial No. 306,661

13 Claims. (Cl. 80—32)

This invention relates, generally, to control systems, and, more particularly, to systems for controlling the tension on strip material as it is being passed through a rolling mill.

In the operation of steel strip rolling mills it is desirable that back and front tensions be applied to the strip as it enters and leaves the working rolls. In some instances it is highly desirable to maintain front and back tensions on the strip of greater magnitude than can be applied through the winding and unwinding reels. It has become the practice, therefore, to provide tensioning devices between the unwinding reel and the working rolls and between the working rolls and the winding reel which will function to provide much higher front and back tensions at the working rolls than the winding and unwinding reel tensions. One such tensioning device for providing front tension on the strip as it leaves the roll stand has been in the form of a pulling device comprising a pair of driven rolls over which a partial wrap of the strip is taken in passing from the roll stand to the winding reel. These two rolls provide the front tension on the strip while the winding tension is independent of the front tension.

Heretofore, the rolls of such pulling devices have been geared together and driven by a single motor. This method of operation has been found unsatisfactory for the reason that small differences in the diameters of the rolls of the pulling device cause slippage and buckling of the strip on the rolls and sometimes cause one of the rolls to carry most of the pulling load.

An object of the invention is to provide a control system for strip tensioning rolls which shall function to distribute the tensioning load between the rolls in a predetermined adjustable proportion which shall maintain the desired tension distribution between the tensioning rolls regardless of the speed of the mill, and which shall be simple and efficient in operation, and inexpensive to manufacture, install, operate, and maintain.

These and other objects and advantages of the invention will be apparent from the following detailed description taken in connection with the accompanying drawings in which:

Figure 1 is a diagrammatic view of a portion of a strip rolling mill embodying the principal features of a preferred embodiment of the invention, and

Fig. 2 is a diagrammatic view of a portion of a strip rolling mill embodying the principal features of another embodiment of the invention.

In practicing the invention, tensioning rolls driven by separate motors are positioned to engage the strip between the winding reel, and a roll stand of a strip rolling mill. Substantially constant excitation is provided for the tensioning roll motors and their relative excitations are adjusted in accordance with the relative tensioning torques that it is desired to have the tensioning rolls exert upon the strip. The armatures of the tensioning roll motors are connected in series circuit relation and energized by the same source of adjustable voltage power as the reel motor and the reducing roll stand motor. An auxiliary generator is connected in series circuit relation with the tensioning roll motors and is so controlled in accordance with armature current of the tensioning roll motors as to maintain the armature current substantially constant. The constant armature current of the tensioning roll motors together with constant excitation of these motors results in the application of a substantially constant tension to the strip.

In the embodiment of Fig. 2 a tensiometer or tension responsive device controls the excitation of the auxiliary generator to maintain the torques of the tensioning roll motors substantially constant.

Referring to Figure 1 for a more detailed description of the invention, the tensioning rolls 2 and 4 driven by the motors 6 and 8, respectively, are positioned to subject the strip 10 to tension as it extends or passes from the rolls of the mill stand 12 to a reel 14. The rolls of the mill stand 12 and the reel 14 are driven by the motors 16 and 18, respectively.

The motors 16 and 18 are supplied with power by a main generator 20 which is continuously driven by any suitable means such as the motor 22. The generator 20 is connected to energize a power bus comprising the conductors 24 and 26. The armature of the roll stand motor 16 is connected to the power bus by a circuit which extends from the conductor 24 through the conductor 28, the armature of the motor 16, and the conductor 30, to the conductor 26. The reel motor 18 is connected to the power bus through a circuit which extends from the conductor 24 through the conductor 32, a controller, as indicated, and a conductor 34 to the conductor 26. The controller is merely indicated and not shown in detail for the reason that any type of controller well known in the art which will function to control the reel motor 18 to maintain substantially constant strip tension may be used. The speed of the motors 16 and 18 is controlled

by varying the voltage of the main generator 20 in a well known manner by means of an adjustable resistor 36 connected in the excitation circuit of its field winding 38.

The field winding 40 of the reel motor 18 is connected to be energized from any suitable source of direct current power represented by the conductors A and B, through a circuit which extends from the conductor A, through the conductors 42 and 44, the controller to which the field winding 40 is connected, and conductors 46 and 48 to the conductor B. The field winding 50 of the roll stand motor 16 is connected to the source of direct current power, as indicated, through a suitable variable resistor 52.

The field windings 54 and 56 of the tension roll motors 6 and 8, respectively, are connected to be energized from the source of direct current power through a circuit which extends from the conductor A, through the conductor 58, a variable resistor 60, conductor 62, the field winding 54, conductor 64, the field winding 56, and the conductor 48 to the conductor B. A shunting circuit including a fixed resistor 66, a variable resistor 68, and a fixed resistor 70 is provided for the field windings 54 and 56. This shunting circuit extends from the conductor 62 through the conductor 72, the resistors 66, 68 and 70, and the conductor 74 to the conductor 48. The selective contact element 76 of the variable resistor 68 is connected by means of the conductor 78 to the conductor 64. This shunting circuit, including the variable resistor 68, provides a means for selectively adjusting the relative values of the excitation of the motors 6 and 8. The variable resistor 68 may be adjusted to provide the desired ratio of field currents in the series connected field windings 54 and 56 and the variable resistor 60 may be adjusted to provide the desired amounts of excitation of the motors 6 and 8.

An auxiliary generator 80 is connected in series circuit with the armatures of the motors 6 and 8 to the power conductors 24 and 26 in a circuit which extends from the conductor 24 through the conductors 32 and 34, the armature of the motor 8, the conductor 34, the armature of the motor 6, the conductor 36, the armature of the auxiliary generator 80, the series field winding 88 of the generator 80 and the conductor 90 to the conductor 26.

The generator 80 is provided with a field winding 92 which is connected across the series field winding 88 of the generator 80 in series with the variable resistor 94 to be energized in accordance with the current in the armatures of the motors 6 and 8, and the generator 80. The field winding 92 is utilized to vary the output potential of the generator 80 and, thus, vary the armature currents of the motors 6 and 8 to compensate for the I. R. drop therein.

The generator 80 is provided with another field winding 96 which is connected to be controlled by a regulator comprising a Wheatstone bridge arrangement 98 and a current responsive solenoid 100. Two opposed junctions of the Wheatstone bridge arrangement 98 are connected, as indicated, by the conductors 102 and 104 to the direct current power conductors A and B. The field winding 96 is connected across the other opposite junctions of the Wheatstone bridge arrangement 98 in a circuit which extends from one of these junctions 105 through a conductor 106, a primary winding 108 of a transformer 110, a conductor 112, the field winding 96, a con-

ductor 114, a variable resistor 116, and a conductor 118 to the other of these junctions 119. The winding of the solenoid 100 is connected to be energized in accordance with the current flowing in the armatures of the motors 6 and 8 and the generator 80 by the potential drop across the series field winding 88 of the generator 80 through a circuit which extends from one side of the series field winding 88, through the conductors 120 and 122, the secondary winding 124 of the transformer 110, the conductor 126, the secondary winding 128 of a transformer 130, a conductor 132, the winding of the solenoid 100, a conductor 134, a variable resistor 136 and conductors 138, 26 and 98, to the other side of the series field winding 88.

The solenoid 100 actuates a movable arm 140 against the bias of a spring member 142. Contact elements 144 and 146 are mounted on the arm 140 to be moved therewith and are positioned to cooperate with a fixed contact element 148. The contact elements 144, 146 and 148 control shunting circuits for the resistor legs 150 and 152 of the Wheatstone bridge 98. The shunting circuit for the resistor 150 extends from the junction 153 through the conductor 154, the contact elements 148 and 144, and the conductor 156 to the junction 105. The shunting circuit for the resistor 152 extends from the junction 153 through the conductor 154, the contact elements 148 and 146, and the conductor 158 to the junction 119.

The primary winding 108 of the transformer 130 is connected to be energized in accordance with the output potential of the generator 80 in a circuit which extends from one side of the armature of the generator 80 through the conductor 120, the winding 108, and a conductor 162 to the other side of the armature of the generator 80.

In the operation of the system, the controller for the reel motor 18 will function as hereinbefore explained to maintain a substantially constant tension on the strip 10 as it is wound on the reel 14, and the regulator comprising the Wheatstone bridge arrangement 98 and the solenoid 100 will function to so control the excitation of the generator 80 as to cause the generator to maintain substantially constant current in the armatures of the tension roll motors 6 and 8. With constant current in the armatures of the motors 6 and 8 and with constant field excitations of these motors, it will be apparent that the torques of these motors will remain substantially constant and that they will exert substantially constant tensions upon the strip 10 through the tensioning rolls 2 and 4.

Considering the operation of the regulator more in detail, any variation in the armature current of the auxiliary generator 80 produces a corresponding variation in the voltage drop across its series field winding 88 and thereby varies the energization of the winding of the solenoid 100 to cause it to lift the movable arm 140 to cause contact elements 146 and 148 to engage. The engagement of these contact elements closes the shunting circuit for the resistor leg 152 of the Wheatstone bridge arrangement to cause an unbalance thereof which in turn will cause current to flow in one direction through the field winding 96 of the auxiliary generator 80. This will produce a change in the output potential of the generator 80, which in turn will cause an impulse to be transmitted through the transformer 130 to the circuit of the winding

of the solenoid 100. Likewise, the energization of the circuit of the field winding 96 will cause an impulse to be transmitted through the transformer 110 to the circuit of the solenoid 100. The secondary windings 124 and 128 of the transformers 110 and 130, respectively, are so connected that the impulses transmitted therethrough by changes of excitation and output potential of the generator 80 will cause movement of the solenoid 100 in the opposite direction to that in which the solenoid 100 previously moved to cause the hereinbefore described changes of excitation and output potential of the generator 80. Thus, after the contact elements 146 and 148 have closed, the impulses transmitted through the transformers 110 and 130 to the solenoid 100 will be such as to cause these contact elements to open and the contact elements 144 and 148 to close. The closure of contact elements 144 and 148 will act to energize the field winding 96 of the generator 80 in the opposite direction, which in turn, will cause the solenoid 100 to move the arm 140 in the direction to open the contact elements 144 and 148 and to close the contact elements 146 and 148. Thus, the contact elements 144 and 146 will be continuously vibrated to excite the generator 80, first in one direction, and then the other. The relative lengths of the alternate periods of energization of the field winding 96 of the generator 80 will be controlled by the armature current of the motors 6 and 8 and the generator 80, which is the main source of energization of the winding of the solenoid 100, and it controls the average position of the arm 140, and, therefore, the relative length of the time of engagement of the contact element 144 with the contact element 148 and the contact element 146 with the contact element 148.

As the mill is started and brought up to speed by variation of the output potential of the main generator 20, the tension on the strip 10 applied by the tensioning rolls 2 and 4 will remain constant because of the constant current regulating effect of the generator 80 in series circuit relation with the armatures of the motors 6 and 8, regardless of the value of the output potential of the generator 20.

It is usually desired to have a greater tension on the strip 10 between roll stand 12 and the tensioning roll 2 than between the reel 14 and the tensioning roll 4. The tensioning roll 2 will have a greater strip pressure upon it, therefore, than the tension roll 4 and will be able to carry a greater part of the tensioning load without slippage upon the strip. To cause the tensioning roller 2 to carry a greater load than the tensioning roller 4, the relative excitations of the motors 6 and 8 may be adjusted by the variable resistor 68 to provide the desired ratio of motor torques. These motor torques will be maintained throughout the range of operation of the mill since their armature currents are maintained constant, and they have a constant field excitation.

The embodiment of the invention shown in Fig. 2 is substantially the same as that of Fig. 1 with the exception that the regulator which controls the excitation of the generator 80 is made responsive to a tension responsive device 179 and constant strip tension is maintained in response to the tension responsive device rather than a current responsive device. Like reference characters designate similar or identical elements of the two systems.

Referring to Fig. 2, a shunting circuit for the

resistor leg 150 of the Wheatstone bridge arrangement 98 extends from the junction 153 through the conductors 102, B, 164 and 166, the contact element 148 which is mounted upon the movable arm 140 actuated by the solenoid 100, contact element 144, and conductor 168 to the junction 105. A similar shunting circuit for the resistor leg 152 of the Wheatstone bridge arrangement 98 extends from the junction 153 through the conductors 102, B, 164 and 166 to the contact element 148, the contact element 146, and the conductors 110 and 118 to the junction 119.

In this embodiment of the invention, the solenoid 100 is merely provided to vibrate the movable contact element 148 between the movable contact elements 144 and 146. The energizing circuit for the winding of solenoid 100 extends from the conductor A through the conductor 172, the variable resistor 136, conductor 174, the secondary 128 of the transformer 130, conductor 126, the secondary winding 124 of the transformer 110, conductor 176, the winding of the solenoid 100, and conductors 178, 166, and 164 to the conductor B.

The engagement of contact element 148 with contact element 146 will close the shunting circuit for the resistor leg 152 causing an unbalance of the Wheatstone bridge 98. This will energize the field winding 96 of the auxiliary generator to change its output potential. The energization of the field winding 96 of the generator 80 and the change of its output potential will cause impulses to be transmitted through the transformers 110 and 130 to the energizing circuit of the winding of the solenoid 100 in such a direction as to cause the contact element 148 to disengage the contact element 146 and to engage contact element 144. This will cause energization of the field winding 96 in the opposite direction which will result in movement of the contact element 148 out of engagement with contact element 146 and into engagement with contact element 145. Thus, the contact element 148 will be made to vibrate continuously and continuous regulation is effected eliminating hunting or excessive variations of strip tension.

The positioning of the contact elements 144 and 146 with respect to the vibrating contact element 148 is controlled by the tension responsive device 179 which comprises a tensioning roller 180 mounted upon an arm of a bell crank 182 in such position as to engage the strip 10 and deflect it from its normal pass line, and a suitable actuating means, such as a fluid pressure operated piston and cylinder arrangement 184. The contact elements 144 and 146 may be actuated in accordance with the movement of the bell crank of the tension responsive device by means of the arm 186 attached thereto. The tension responsive device is so adjusted that variations in strip tension will vary the deflection of the strip and, therefore, the position of the contact elements 144 and 146 with respect to the vibrating contact element 148. Thus, the relative lengths of excitation of the generator 80 in one direction and the other are controlled by the tension of the strip and automatically function to maintain a substantially constant strip tension.

It is to be understood that the application of the control system to a rolling mill between the roll stand and a winding reel is merely illustrative and that the system may be used equally well to control the tension between two roll stands of a tandem mill or between an unwinding reel and

a roll stand. In the event that the system is used to control the back tension on the strip between an unwinding reel and a roll stand, the dynamo-electric machines 6, 8 and 18 would be operated as drag generators and the system would function to control the amount of braking torque applied to the strip by these drag generators.

It is to be further understood that as many tensioning rolls and their associated dynamo-electric machines as desired may be provided, the system being applicable to several tensioning rolls in the same manner as it is applied to two tensioning rolls in the illustrated embodiments of the invention.

It will be seen that I have provided a control system for a strip tensioning device which shall function to distribute and maintain the desired strip tension between a plurality of driven tensioning rolls regardless of the speed of the mill, which shall compensate for the I. R. drop in the dynamo-electric machines connected to the tensioning rolls, which shall be simple and efficient in operation, and inexpensive to manufacture, install, operate and maintain.

In compliance with the requirements of the patent statutes, I have shown and described herein in the preferred embodiments of my invention. It is to be understood, however, that the invention is not limited to the precise constructions shown and described, but is capable of modification by one skilled in the art, the embodiments herein shown being merely illustrative of the principles of my invention.

I claim as my invention:

1. In a strip tension control system for a pair of tensioning rolls over which the strip passes in travelling between a roll stand and a reel of a strip rolling mill, in combination, a separate dynamo-electric machine connected in driving relation with each of the tensioning rolls, means connecting the armatures of said dynamo-electric machines to a source of potential to which the roll stand and reel motors are connected and which is selectively variable to vary the speed of the mill, and auxiliary generator connected in series circuit relation with said dynamo-electric machines, means providing selectively adjustable substantially constant excitations for said dynamo-electric machines, and means for so controlling the said auxiliary generator as to cause said dynamo-electric machines to exert substantially constant torques on the strip regardless of variations in the value of the potential of the source of potential which energizes the reel and roll stand motors.

2. In a control system for a plurality of tensioning rollers over which a strip of material passes in a partial wrap as it extends between adjacent work devices for controlling the tension on the strip of material as it passes between the work devices which are connected in driving relation with dynamo-electric machines whose armatures are energized from a power source of selectively adjustable potential, in combination, a separate dynamo-electric machine connected in driving relation with each of the rollers, means connecting the armatures of said roller dynamo-electric machines to the source of adjustable potential to which the work device dynamo-electric machines are connected, means providing separately selectively adjustable substantially constant excitations for said roller dynamo-electric machines, a generator connected in series circuit relation with said roller dynamo-electric machines, and means for so controlling

said generator as to cause said roller dynamo-electric machines to exert substantially constant torques on the strip regardless of variations in the value of the potential of the power source.

3. In a control system for a plurality of tensioning rollers over which a strip passes in a partial wrap as it extends between adjacent work devices for controlling the tension on the strip as it passes between the work devices which are connected in driving relation with dynamo-electric machines whose armatures are energized from a power source of selectively adjustable potential, the combination of a separate dynamo-electric machine connected in driving relation with each of the rollers, means connecting the armatures of said roller dynamo-electric machines to the source of adjustable potential to which the work device dynamo-electric machines are connected, means for providing and maintaining substantially constant ratios between the excitations of the roller dynamo-electric machines, a generator, means connecting said generator armature in circuit with the armatures of said roller dynamo-electric machines, and means for so controlling said generator as to cause said roller dynamo-electric machines to exert substantially constant torques on the strip regardless of variations in the potential of the power source.

4. In a control system for a plurality of tensioning rollers over which a strip passes in a partial wrap as it extends between adjacent work devices for controlling the tension on the strip as it passes between the work devices which are connected in driving relation with dynamo-electric machines whose armatures are energized from a power source of selectively adjustable potential, the combination of a separate dynamo-electric machine connected in driving relation with each of the rollers, means connecting the armatures of said roller dynamo-electric machines to the source of adjustable potential to which the work device dynamo-electric machines are connected, means providing selectively adjustable substantially constant excitations for said roller dynamo-electric machines, a generator, means connecting said generator in circuit with said roller dynamo-electric machines, and means responsive to the armature current of said roller dynamo-electric machines for so controlling said generator as to maintain substantially constant current in the armatures of said roller dynamo-electric machines regardless of variations of the potential of the said power source.

5. In a control system for a plurality of tensioning rollers over which a strip passes in a partial wrap as it extends between adjacent work devices for controlling the tension on the strip as it passes between the work devices which are connected in driving relation with dynamo-electric machines whose armatures are energized from a source of selectively adjustable potential, the combination of a separate dynamo-electric machine connected in driving relation with each of the rollers, means connecting the armatures of said roller dynamo-electric machines to the source of adjustable potential to which the work device dynamo-electric machines are connected, means providing selectively adjustable substantially constant excitations for said roller dynamo-electric machines, a generator connected in circuit with said roller dynamo-electric machines, and means responsive to the strip tension for so controlling said generator as to maintain sub-

stantially constant tension on the strip regardless of variations of the potential of the said power source.

6. In a control system for a plurality of tensioning rollers over which a strip passes in a partial wrap as it extends between adjacent work devices for controlling the tension on the strip as it passes between the adjacent work devices which are connected in driving relation with dynamo-electric machines whose armatures are energized from a power source of selectively adjustable potential, the combination of a separate dynamo-electric machine connected in driving relation with each of the rollers, means connecting the armatures of said roller dynamo-electric machines to the source of adjustable potential to which the work device dynamo-electric machines are connected, means for providing and maintaining substantially constant ratios between the excitations of the roller dynamo-electric machines, a generator, compensating means providing an excitation for said generator proportional to the armature currents of said roller dynamo-electric machines, means connecting said generator armature in circuit with the armature of said roller dynamo-electric machines, and means for so controlling said generator as to cause said roller dynamo-electric machines to exert substantially constant torques on the strip regardless of variations in the potential of the power source.

7. In a control system for a plurality of tensioning rollers over which a strip passes in a partial wrap as it extends between adjacent work devices for controlling the tension on the strip as it passes between the work devices which are connected in driving relation with dynamo-electric machines whose armatures are energized from a power source of selectively adjustable potential, the combination of a separate dynamo-electric machine connected in driving relation with each of the rollers, means connecting the armatures of said roller dynamo-electric machines to the source of adjustable potential to which the work device dynamo-electric machines are connected, means providing selectively adjustable substantially constant excitations for said roller dynamo-electric machines, a generator, means connecting said generator in circuit with said roller dynamo-electric machines, compensating means providing an excitation for said generator proportional to the armature currents of said roller dynamo-electric machines, and means responsive to the armature current of said roller dynamo-electric machines for so controlling said generator as to maintain substantially constant current in the armatures of said roller dynamo-electric machines regardless of variations of the potential of the said power source.

8. In a control system for a plurality of tensioning rollers over which a strip passes in a partial wrap as it extends between adjacent work devices for controlling the tension on the strip as it passes between the work devices which are connected in driving relation with dynamo-electric machines whose armatures are energized from a source of selectively adjustable potential, the combination of a separate dynamo-electric machine connected in driving relation with each of the rollers, means connecting the armatures of said roller dynamo-electric machines to the source of adjustable potential to which the work device dynamo-electric machines are connected, means providing selectively adjustable substantially constant excitations for said roller dynamo-

electric machines, a generator, means connecting said generator in circuit with said roller dynamo-electric machines, compensating means providing an excitation for said generator proportional to the armature currents of said roller dynamo-electric machines, and means responsive to the strip tension for so controlling said generator as to maintain substantially constant tension on the strip regardless of variations of the potential of the said power source.

9. In a control system for a pair of tensioning rollers over which a strip of material passes in a partial wrap as it passes between a rolling mill and a winding reel for controlling the tension on the strip of material as it is delivered from the rolling mill and wound onto the winding reel which mill and reel are connected in driving relation with motors whose armatures are energized from a power source of selectively adjustable potential, the combination of a separate drive motor for each of the rollers, means connecting the armatures of said roller motors to the power source to which the mill and reel motors are connected, means providing selectively adjustable substantially constant excitations for said roller motors, a generator, means connecting said generator in circuit with said roller motors, and means for so controlling said generator as to cause said roller motors to exert substantially constant torques on the strip regardless of variations in the potential of the power source.

10. In a control system for a pair of rollers over which a strip of material passes in a partial wrap as it passes from an unwinding reel to a rolling mill for controlling the tension on the strip of material as it is fed to the rolling mill from the unwinding reel which mill and reel are connected in driving relation with a drive motor and a drag generator, respectively, which drive motor and drag generator are connected to a power source of selectively adjustable potential, the combination of a separate drag generator driven by each of the rollers, means connecting the armatures of said roller drag generators to the power source to which the reel drag generator and the mill motor are connected, means providing selectively adjustable substantially constant excitations for said roller drag generators, an auxiliary generator, means connecting said auxiliary generator in circuit with said roller drag generators, and means for so controlling said auxiliary generator as to cause said roller drag generators to exert substantially constant torques on the strip regardless of variations in the potential of the power source.

11. In a system for controlling the tension on a strip of material as it is delivered from a rolling mill and wound onto a winding reel which mill and reel are connected in driving relation with motors whose armatures are energized from a power source of selectively adjustable potential, the combination of a pair of rollers over which the strip passes in a partial wrap as it passes from the mill to the reel, a separate drive motor for each of said rollers, means connecting the armatures of said roller motors to the power source to which the mill and reel motors are connected, means providing selectively adjustable substantially constant excitations for said roller motors, a generator, means connecting said generator in circuit with said roller motors, and means responsive to the strip tension for so controlling said generator as to maintain substantially constant tension on the strip regard-

less of variations of the potential of the said power source.

12. In a system for controlling the tension on a strip of material as it is delivered from a rolling mill and wound onto a winding reel which mill and reel are connected in driving relation with motors whose armatures are energized from a power source of selectively adjustable potential, the combination of a pair of rollers over which the strip passes in a partial wrap as it passes from the mill to the reel, a separate drive motor for each of said rollers, means connecting the armatures of said roller motors to the power source to which the mill and reel motors are connected, means providing selectively adjustable substantially constant excitations for said roller motors, a generator, means connecting said generator in circuit with said roller motors, and means responsive to the strip tension for so controlling said auxiliary generator as to maintain substantially constant tension on the strip regardless of variations of the potential of the said power source.

13. In a system for controlling the tension on a strip of material as it is delivered from a rolling mill and wound onto a winding reel which mill and reel are connected in driving relation with 5 motors whose armatures are energized from a power source of selectively adjustable potential, the combination of a pair of rollers over which the strip passes in a partial wrap as it passes from the mill to the reel, a separate drive motor 10 for each of said rollers, means connecting the armatures of said roller motors to the power source to which the mill and reel motors are connected, means providing selectively adjustable substantially constant excitations for said roller 15 motors, a generator, means connecting said generator in circuit with said roller motors, and means responsive to the armature current of said roller motors for so controlling said generator as to maintain substantially constant current in the armatures of said roller motors regardless of variations of the potential of the said power source.

WILLARD G. COOK.
